UNITED STATES PATENT OFFICE.

HERBERT J. BRAGDON, OF ALTON, ILLINOIS.

AMMUNITION-SHELL-FEEDING MACHINE.

1,408,497.

Specification of Letters Patent. Patented Mar. 7, 1922.

Application filed June 26, 1919. Serial No. 306,959.

To all whom it may concern:

Be it known that I, HERBERT J. BRAGDON, a citizen of the United States, residing at Alton, county of Madison, State of Illinois, 5 have invented a certain new and useful Ammunition-Shell-Feeding Machine, of which the following is a specification, reference being had to the accompanying drawings, forming a part thereof.

10 This invention relates generally to material feeding-machines and, more particularly, to a certain new and useful machine especially adapted for handling and feeding ammunition shells during the manufacture 15 thereof.

The principal object of my present invention is to provide a machine comprising mechanism capable of efficiently picking up 20 the shells and automatically successively feeding or discharging the shells with their ends relatively disposed in the same direction.

With the above and other objects in view, my present invention resides in the novel 25 form, construction, arrangement, and combination of parts hereinafter described and afterwards pointed out in the claims.

In the accompanying drawings,

Figure 1 is a view partly in side elevation and partly in longitudinal section of a machine constructed in accordance with 30 and embodying my invention, the view being taken approximately on the line 1—1, Figure 2;

Figure 2 is a transverse sectional view of the machine taken approximately on the line 35 2—2, Figure 1, with parts broken away;

Figure 3 is a fragmental perspective view 40 of the machine, showing a selected shell as it is picked up or in its first step of movement;

Figure 4 is a similar view, showing the selected shell as it is guided and carried out of the mass;

45 Figure 5 is a similar view, showing the selected shell carried or moved to overlie an open-mouthed discharge chute and the means for engaging the shell to cause the same to drop into the chute with its base or 50 heavier end foremost in descent;

Figure 6 is a view corresponding approximately to Figure 5, showing a slightly modified form of teeter especially adapted for bullet-slugs and the like; and

55 Figure 7 is a plan view of such modified form of teeter.

Referring now to the said drawings, in which like reference characters refer to like parts throughout the several views, 1 indicates a suitable base adapted to be bolted or 60 otherwise rigidly fixed to and upon a suitable support. Forming part of base 1, is a yoke 2 preferably inclined to the horizontal, as shown. Fixed in and supported by the yoke 2, is a hopper 3, whose bottom is 65 correspondingly inclined rearwardly and downwardly, whereby shells or other materials delivered or dropped into the hopper will move by gravity toward its lower or rear end. Preferably the hopper 3 is constructed of suitable sheet metal and of semi-cylindrical section, with its top and both ends open.

Fitted and suitably fixed within the hopper 3 intermediate its ends, is a diaphragm 75 4 preferably of circular or disk form and flanged rearwardly at its periphery. Formed in the diaphragm 4 at and adjacent the inclined bottom of the hopper 3 and preferably wholly to one side of the longitudinal 80 median line thereof, is a hole or aperture 5; and provided in the hopper 3 to the rear of the diaphragm 4, is an open-top shell-receiver 6, which extends through the bottom of the hopper 3 on the opposite side of 85 the longitudinal median line thereof, and which has connected thereto and forms substantially a part of a tube 7, which, in turn, leads to a loading or other machine or other place where it is desired to deliver the 90 handled shells.

Suitably formed on the rear face of the diaphragm 4, is a seat 8, upon which a suitable housing 9 is seated and fixed to the diaphragm 4 by means such as the 95 screws 10. Extending rearwardly from the housing 9 is a sleeve 11 carrying at its rear or free end a fixed disk 12. This fixed disk 12 is disposed adjacent the rear end of the hopper 3, but is spaced therefrom at 100 its periphery, as shown, to receive and accommodate between its periphery and the hopper the ammunition-shells or other articles or materials being handled, disk 12 having a diameter somewhat less than the diameter of the hopper for such purpose. The peripheral edge 13 of the disk 12, which at the rear of the disk is cut away or stepped, as at 14, for purposes shortly appearing, performs an important function in 105 the machine and will be hereinafter appropriately designated the "track."

Formed radially in the disk 12, is a cut-out 15, which breaks at the top of the machine the continuity of the track 13. Such cut-out 15 will be hereinafter referred to as 5 the "gap," and arranged in and registering with the gap at its upper end, is an open-ended chute or way 16, which inclines downwardly and somewhat forwardly and whose lower end stands over, but is spaced from, 10 the upper end of the receiver 6 of the tube 7.

Located in the rear of, but closely adjacent to, the fixed disk 12, and rotatable in a plane approximately parallel with the plane of the disk 12, is a rotary disk or carrier 17 having a stub-shaft 18 journaled for rotation in the sleeve 11. Fixed on the forward end of the shaft 18 and located within the housing 9, is a worm-wheel 19, which engages with the housing 9, as shown, to 15 hold the carrier-disk 17 against axial movement or displacement. Within the housing 9, in mesh with the wheel 19, is a worm 20 fixed on or integral with a rotary shaft 21 suitably journaled in the machine. The 25 shaft 21 extends at one end outside the hopper 3, as shown, and carries at its outer end suitable variable speed pulleys 22 adapted for belt or other driven connection with a suitable source of power.

30 The rotary disk or carrier 17 is thickened or enlarged at its periphery, as at 23, and formed or provided on its inner surface next its periphery with a rearwardly and inwardly inclined or beveled face 24; and at 35 regular intervals around the disk 17 or circumferentially, so to speak, there are fixed to the disk 17 at its said face 24 paddles 25, which extend forwardly into the hopper 3 in the said space provided between the periphery of the fixed disk 12 and the hopper 40 and override the track 13. Also fixed to the disk 17 at its face 24, and respectively suitably adjacent and spaced forwardly from each paddle 25 in the direction of rotation 45 of the disk 17, are pins 26, which extend forwardly relatively to the hopper and preferably at right angles to the plane of the face 24.

Assuming, for illustration, the hopper to 50 be secured in position to receive shells dropped from a base-fitting machine and the delivery-tube 7 with its discharge end over a shell-loading machine and the shaft 21 driven, that is rotated, through the pulleys 55 22 and a belt-connection (not shown) extended to "power", the operation of the machine is as follows:

Due to the inclination of the hopper, the shells received therein move by gravity to 60 the diaphragm 4 and to and through the hole or aperture 5 therein to the rear of the hopper, the hopper or aperture 5 being preferably of such dimensions as to limit the flow or supply of shells to a number in which the 65 "mass" weight does not interfere with the

proper functioning of the track 13 and paddles 25. The inclined or beveled face 24 of the rotary disk 17 forms with the bottom of the hopper what might well be described as a trough, and the shells, so moving, as 70 described, to the rear of the hopper, move into this trough and temporarily there reside in the path of the paddles 25 and beneath the track 13, as illustrated in Figure 3. The disk 17 rotating, the paddles 25 successively 75 engage and pick up the shells one by one, each paddle moving its picked up or so-called selected shell over and upon the track 13, as illustrated in Figure 4, until the shell, on the continued movement of the disk 17, 80 reaches the gap 15 or until the shell has reached approximately the position illustrated in Figure 5, the so picked up or selected shells being maintained in lengthwise position upon, and as they are carried 85 around on, the track 13 by reason of the inclination to the horizontal of the disks 12 and 17.

The shells in the hopper form a conglomerate mass, and the paddles 25 gather 90 or pick up and move the shells to the gap 15 without end for end definition. To the end now that the shells may be delivered to the loading machine with their ends relatively disposed in the same direction, I 95 relate the pins 26 to the paddles 25, each pin constituting or providing a so-called shell-teeter.

It will be noted that the pins 26 project at 100 their forward end relatively close to the disk 12 and, reference being had to the top of the machine, somewhat below the plane of the track 13, the forward projecting ends of the pins 26 being accommodated by the step or cut-out 14 in the disk 12.

Now, as each particular or so-called selected shell reaches and is moved over the gap 15 by its particular paddle 25, the shell first falls or drops upon, and is temporarily suspended over the gap by the particular 110 adjacent pin 26. The shell then, irrespective of which of its ends is presented forwardly on the pin, reference being had to the direction of travel of the disk 17, will be tipped over the pin in one or the other 115 direction, by reason of the preponderance of weight at its base, to slide from the pin base downward into the chute, as indicated by dotted lines in Figure 2, and from the chute into the receiver 6 and to the loading 120 machine. Advantage being so taken of the fact that all metallic shells are considerably heavier at one end, on account of surplus material left to form the head for holding the primer or firing-cap, the shells are thus, 125 as described, automatically successively delivered or discharged from the machine with their ends relatively disposed in the same direction.

The present machine is capable of han- 130

dling and feeding without alteration or change a wider range of lengths, diameters, and shapes of metallic shells than any other machine of which I am aware; more precisely, the present machine is capable of handling and feeding without alteration or change shot-gun or paper-tube shells of 28-gauge up to and including 10-gauge, and it may be stated that the receiver 6 and tube 7, as well as also the chute 16 for the greater part of its length, are preferably of a diameter or size sufficient only to accommodate the passage therethrough of a single stream end to end of shells of the gauges named. As before stated, the chute 16 has its lower or reduced portion spaced at its lower end from the upper end of the receiver 6, into which receiver the shells fall with some velocity due to their drop; it may now be added that such space is of a width preferably approximating one and one-half times the length of the longest shell which the particular machine is designed to handle and feed. Consequently, it will be noted that, upon stoppage of the shells at the delivery end of the tube 7, the shells will not jam in the tube as the carrier 17 and its paddles 25 continue to operate, but will fall back into the hopper at the said space or gap provided between the chute 16 and receiver 6, as indicated by dotted lines in Figure 2. It may be stated also that any shells engaged by the paddles and not fully positioned upon the track as described will fall by gravity from the track and back into the hopper or trough before reaching the gap or chute, and that, due to the fact that the shells are continually being carried by the paddles away from the discharge-tube or receiver, it is practically impossible for the shells to pile up around or otherwise interfere with the discharge-tube or receiver.

It will be noted further that the paddles 25 are preferably disposed, as shown, at an angle to the axis or center line of the disk 17, and that the pins 26 incline downwardly and inwardly. The paddles and pins being so disposed, not only will the shells tilt upon the pins without hanging or clinging to the pins and paddles, but also the paddles are enabled to more facilely ride or travel through the mass of shells and with approximately just sufficient agitation to guarantee a flow without damaging the shells from or by excessive agitation. The present machine has been found from actual use to feed ninety per cent or better, that is to say, ninety of every one hundred paddles will deliver shells to the gap 15, such performance insuring a steady flow of shells at low speed and with agitation of the shells reduced approximately to a minimum. To permit foreign matter, metallic dust, and the like to find convenient outlet or escape from the machine, I preferably slot the hopper, as at

27, in the base of the described trough. I may also add that the disk-face 24 is so beveled and the pins 26 correspondingly so located as to permit and afford a ready and quick release of the shells into the gap without hanging or binding. 70

While I have herein specifically described my machine in connection with the feeding of ammunition-shells to a loading machine, for which use it is especially adapted, it is 75 to be understood that the machine may equally well be used for feeding various other materials or articles to machines of various type, such, for instance, as presses, trimmers, headers, and the like. And in 80 Figures 6 and 7, I show the machine slightly modified and thereby adapted for handling such articles as bullet-slugs. As so modified, I substitute for the pins 26 upon the disk or carrier 17 teeter-members in the form of 85 plates 26' and relate thereto upon the disk or carrier 17, as shown, paddles 25'. Each plate 26' is cut away within its area to provide a main aperture or slot 28 and communicating oppositely and centrally disposed 90 extensions 28' and 28'' at its ends, main slot 28 having a width slightly greater than the diameter of the particular slug, each reduced extension 28' and 28'' having a width sufficient only to accommodate the head of 95 the slug, and main slot 28 combined or together with one or the other of its said extensions having a length somewhat less than the length of the particular slug, as seen in Figure 7. As seen in Figure 6, each paddle 100 25' is so positioned upon the disk 17 relatively to its companion teeter-plate 26' as to extend at its lower edge preferably approximately flush with the rear edge α of, and due to its inclination to somewhat overhang, rear slot-extension 28'. It is also to be noted that both the plate 26' and paddle 25' travel with the disk 17, the plate 26' further being so positioned upon the disk 17 relatively to the track 13 that the track 110 13 forms or provides, as it might be described, a false bottom for the plate-slot as the plate is being carried over the track in the rotations of the disk 17. Consequently, as the slugs are picked up and positioned by 115 the paddles upon the plates, the slugs are prevented from falling through the plate-slots by the track disposed therebeneath and thus travel with the disk 17 until each respective plate is positioned above the gap 120 15. When so positioned above the gap 15, irrespective of which end thereof is positioned forwardly, the reduced end of the slug will first drop through one or the other of the reduced slot-extensions, the body of 125 the shell or slug being teetered on one or the other edge of the main slot 28 and the shell thus dropping head down into the chute 16 and from thence out of the machine. Thus I again deliver such articles 130

from the machine with their ends definitely disposed in the same direction. I might add that the slug is held lengthwise upon the plate 26' by the beveled face 24 of the carrier 17, the plate 26' being tilted or disposed slightly out of horizontal, so that when in position as illustrated in Figure 7, the slug will roll back and rest against the face 24 of the carrier, which face is so related to the plate as to maintain the slug in proper position relatively to the plate-slot to fall therethrough as described as soon as the plate has been carried around above the gap 15 in the track. It frequently happens in actual practice that unformed slugs become mixed with the good or properly formed slugs. Should an improperly formed slug be picked up by one of the paddles and positioned as described upon its companion plate, the slug would not drop or fall through the plate-slot as the plate-slot is positioned above the gap. In such case, the slug would remain on the plate and be carried again on the track and down the opposite side of, and then into, the hopper. Although not here shown, it will be evident that, if a suitable opening were provided in the machine, such scrap or improperly formed slug would then drop from the machine. Thus my machine becomes and performs the function, so to speak, of an automatic inspector especially when employed in connection with materials of this type.

I am aware that changes in the form, construction, arrangement, and combination of the several parts of my machine may be made and substituted for those herein shown and described without departing from the nature and principle of my invention.

Having thus described my invention, what I claim and desire to secure by Letters Patent is:

1. A feeding-machine for ammunition shells and the like including, in combination, a trough, a fixed annular track having a gap, and an annular series of spaced paddles adapted for movement through the trough for picking up the shells and conveying the same endwise one by one from the trough and along the track to its gap for discharge from the machine.

2. A feeding-machine for ammunition shells and the like including, in combination, a trough for the shells, a fixed annular track having a gap, an annular series of spaced paddles adapted for movement through the trough for picking up the shells and conveying the same endwise one by one from the trough and along the track to its gap without a definite end for end disposition of the shells, and means for causing the shells at said gap to successively discharge from the machine with their ends disposed definitely in the same direction.

3. A feeding machine for ammunition-

shells and the like including, in combination, a trough for the shells, a fixed annular track having a gap, means comprising an annular series of spaced paddles adapted for movement through the trough for picking up and conveying the shells one by one from the trough and along the track to its gap without a definite end for end disposition of the shells, and means for teetering the shells at said gap to cause the same to successively discharge from the machine with their ends disposed definitely in the same direction.

4. A feeding-machine for ammunition shells and the like including, in combination, a trough for the shells, a fixed track having a gap, a series of spaced paddles adapted for movement through the trough for picking up the shells and conveying the same one by one from the trough and along the track to its gap without a definite end for end disposition of the shells, and means comprising a series of teeter-pins for causing the shells at said gap to successively discharge from the machine with their ends disposed definitely in the same direction.

5. A feeding-machine for ammunition shells and the like including, in combination, a trough for the shells, a fixed annular track having a gap, an annular series of spaced paddles adapted for movement through the trough for picking up the shells and conveying the same one by one from the trough and along the track to its gap without a definite end for end disposition of the shells, and means comprising a series of teeter-pins for causing the shells at said gap to successively discharge from the machine with their ends disposed definitely in the same direction.

6. A feeding-machine for ammunition shells and the like including, in combination, a trough for the shells, a fixed disk providing at its periphery a track having a gap, a rotary disk, means for rotarily actuating the rotary disk, an annular series of spaced paddles carried by the rotary disk for movement through the trough for picking up the shells and conveying the same one by one from the trough and along the track to its gap without a definite end for end disposition of the shells, and an annular series of teeter-pins carried by the rotary disk and disposed respectively adjacent the paddles for causing the shells at said gap to successively discharge from the machine with their ends disposed definitely in the same direction.

7. A feeding-machine for ammunition shells and the like including, in combination, a trough for the shells, a fixed disk providing at its periphery an annular track having a gap, a rotary disk provided adjacent its periphery with a beveled face, means for rotarily actuating the rotary disk, an an-

nular series of spaced paddles carried by the rotary disk at its said beveled face and each disposed at an angle to the axis of the disk for movement through the trough for 5 picking up the shells and conveying the same endwise one by one from the trough and along the track to its gap without a definite end for end disposition of the shells, and an annular series of teeter-pins projecting

from the beveled face of the rotary disk and 10 disposed respectively adjacent the paddles for causing the shells at said gap to successively discharge from the machine with their ends disposed definitely in the same direction.

15

In testimony whereof, I have signed my name to this specification.

HERBERT J. BRAGDON.
